UNITED STATES PATENT OFFICE.

HENRY A. LAUSON AND JOHN J. NORMAN, OF CHICAGO, ILLINOIS, AND
ABRAM D. NOTT, OF JANESEVILLE, WISCONSIN.

GAS-ENGINE.

SPECIFICATION forming part of Letters Patent No. 550,451, dated November 26, 1895.

Application filed June 4, 1894. Serial No. 513,491. (No model.)

To all whom it may concern:

Be it known that we, HENRY A. LAUSON and JOHN J. NORMAN, residing at Chicago, county of Cook, and State of Illinois, and ABRAM D. NOTT, residing at Janesville, county of Rock, and State of Wisconsin, citizens of the United States, have invented certain new and useful Improvements in Gas-Engines, which are fully set forth in the following specification, reference being had to the accompanying drawings, forming a part thereof.

In the drawings, Figure 1 is a partly-sectional plan of a gas-engine embodying our improvements, section being made at the horizontal plane of the axis of the main crank-shaft and through the power-communicating pulley and two bevel-gears through which motion is communicated from the main shaft to the valve-operating shaft and governing mechanism. Fig. 2 is a vertical section at the line 2 2 on Fig. 1, showing the governing mechanism. Fig. 3 is a detail section at the line 3 3 on Fig. 1 through the axis of the carburetor and gas-inlet valve and chamber. Fig. 4 is a detail plan of the mechanism through which the governor operates to interrupt the gas supply when the speed exceeds the desired limit. Fig. 5 is a detail vertical section at the line 5 5 on Fig. 1, showing part of the same mechanism which is shown in Fig. 4. Fig. 6 is a rear or back side elevation of a bevel gear-wheel through which power is communicated to the governor-operating shaft. Fig. 7 is a detail section at the line 7 7 on Fig. 6. Fig. 8 is a detail elevation of a portion of a carbureting-chamber and a vane wheel which revolves therein. Fig. 9 is a detail end elevation showing the connection by which the lighter-valve and the exhaust-valve are operated.

The title "gas-engine" is used in our specification and claims to denote any engine in which the explosion of gas affords the motive power without regard to whether the gas is or is not generated in the machine.

The gas-engine to which our improvements relate is of the class or type in which the piston makes two complete reciprocations for each charge or explosion of gas—that is, in which the charge is first exploded, producing the outward movement of the piston, whose

return movement expels the gases of combustion, the next outward movement drawing in a charge of mixed gas and air, which is compressed by the return movement and exploded to produce the next outward movement, four movements thus constituting the complete cycle of the piston.

Our improvements relate to the mechanism for governing the engine by controlling the gas-inlet, and to the carburetor or vaporizing or mixing chamber in which oil may be converted into gas and the gas is mixed with air or fitted for explosion in the cylinder to generate the motive force, and it involves, also, certain details as to the arrangement of the parts in question with a view to compactness and simplicity.

The engine rests upon the bed A, upon which are formed the bearings A' A' for the main crank-shaft b, to which the fly-wheel B is secured at one end, while at the other end there is secured a bevel gear-wheel B', and conveniently, also, a band-wheel B², for communicating power to mechanism to be driven by the engine.

C is the cylinder, mounted on the bed A horizontally. The usual construction of the piston-and-pitman connection for the same is employed and not shown in detail. The interior construction of the cylinder and associated passages, in which the explosion is produced and through which the exhaust-gases are carried off, is also without illustration in the drawings as not embodying any inventions which are claimed in this application. The location of the several parts exteriorly may, however, be indicated to facilitate a general understanding of the structure.

D is the gas-inlet-valve chamber; E, the exhaust-valve chamber; F, the lighter-valve chamber.

To the forward side of the base A are secured the several brackets, upon which are mounted various parts of the valve operating and governing mechanism. The gas-inlet-valve chamber D is thus secured, as indicated, by the bolts d d. The governor-bracket G is thus secured by bolts, one of which is seen at g, and the inlet-valve-operating plunger has its bearings in the bracket H, secured by bolts, (not seen, but which are passed

through the holes h , Fig. 5.) The brackets D and H also have at their forward sides the journal-boxes D' and H', which afford bearings for the shaft J.

5 The shaft J is driven by the large bevel-gear J', which is fixed upon its end beyond the bearing H' and which meshes with and is driven by the bevel-gear B' on the main crank-shaft b. The shaft J and the wheel J' upon it operate all the valves which control the action of the piston, and since the valves are opened and closed once for each two reciprocations of the piston the shaft J makes one revolution for each two revolutions of the 15 main crank-shaft b, and the bevel-gear J' has therefore twice the number of teeth of the bevel-gear B', which drives it. The lighter-valve, whose stem k is journaled in the arm F' of the bracket having the lighter-valve chamber, is actuated by the eccentric pin j at the end of the shaft J, said pin operating against the antifriction-roll k', mounted at the outer end of the plunger or valve-stem k. The exhaust-valve is operated by the cam J², 25 which is fixed on the shaft J beyond the bearing D', the lever E' having the antifriction-roll e', serving to communicate motion to the valve (not shown) in the valve-chamber E. The operation of the gas-inlet valve is more 30 intimately related to this invention and will be described in detail. In Fig. 3 there is shown said gas-inlet valve L, seating at the opening d', which leads into the valve-chamber from which the opening D' leads into the 35 cylinder.

The valve-chamber is formed in the same casting with the carburetor or vaporizing chamber M, and with a gas-passage M' intermediate between the valve-chamber D and the 40 carburetor or vaporizing or mixing chamber M. The stem L' of the valve extends out through the valve-seat d' and through a long sleeve or slide bearing M¹⁰, provided for said stem in the casting and protruding into the 45 passage M', and also protruding from the casting outwardly, as the boss M¹¹. The spring N, coiled about the protruding sleeve or boss M¹¹, and also about the stem L', which protrudes from the boss, is stopped one end against the 50 chamber and the other end against an adjusting-nut N' on the stem L'. This spring is designed to be normally under compression and adapted to react to force the stem outward to seat the valve. The valve-stem L' is 55 virtually joined at L¹⁰ beyond the nut N' to the remaining section of the stem L¹¹, although it only abuts against the end of the latter section L¹¹; but by reason of the structure the two parts are in constant contact and operate precisely as if hinged together at the point of contact. The section L¹¹ obtains a bearing in the lugs G² on the bracket G, and is suspended at the other end in the end of the vertical arm P of the governor bell-crank lever hereinafter described. The bearing in the 60 lug G² is tapered, widening toward the suspended end, so that the rod or stem L¹¹ can

swing horizontally in said bearings about its point of contact with or hinging to the outer end of the stem L'. The oscillating end of the stem L¹¹ is wedge-shaped, with its edge vertical. In the bracket H there is journaled the plunger L¹², which is in line with, the stem L' and with the continuation L¹¹ of that stem when the latter is in normal position—that is, 70 except when it is deflected by the governor at high speed, as hereinafter explained. The end of the plunger L¹² toward the wedge-shaped end of the stem L¹¹ is provided with a terminal l¹², which has a vertical notch 80 adapted to receive the wedge-shaped end of the stem L¹¹ when said stem is in line with the plunger and the stem L'. This terminal, however, ends in acute angles at the lateral margins of the wedge-shaped notch, so that 85 if the point of the wedge misses the notch it will slide past the end of the terminal and fail to make any engagement with it. This terminal l¹² has a stem by which it is screwed into the end of the plunger L¹², and is provided with a jam-nut l²⁰, by which its adjustment may be fixed. The plunger L¹² has a longitudinal aperture l¹³, in which a spring L¹³ is lodged, and reacting against one end of the aperture and against a lug h², which projects 95 down into it from the cover H² of the bracket H, tends to hold the plunger to the right—that is, away from the stem L¹¹. The right-hand end of the plunger outside of its bearing in the bracket H is provided with an 100 antifriction-roll L¹⁴, upon which the cam J¹⁰, hereinafter described, and which is mounted on the wheel J', operates to reciprocate the plunger. On the shaft J, in addition to the bevel-gear J', there is a bevel-gear J⁸, which meshes with and drives the bevel-gear O on the lower end of the vertical sleeve or hollow shaft o, which is journaled in the bracket G and stopped against downward movement by the cross-head o' at its upper end and against 110 upward movement by the hub of the gear o. To the cross-head are pivoted at its opposite ends the governor-arms O' O', which have the inwardly-projecting lever-fingers O¹⁰ O¹⁰, which overhang the flange O²⁰ on a thrust-rod O², which reciprocates through the sleeve o and at its upper end is connected to the lever-arm P' of the bell-crank lever P P', which is fulcrumed at p on the arm G⁸ of the bracket G and at its lower end engages 115 and supports the rod or section L¹¹ of the valve-stem, and intermediate the fulcrum and said lower end is pressed by the spring Q reacting against the arm G⁸, through which an adjusting-screw Q' is set and secured by a 120 jam-nut Q' to regulate the tension of the spring. 125

The connection of the horizontal arm of the bell-crank lever to the thrust-rod O² is effected by means of the two-part collar O³, which is peripherally grooved to receive the fork p' of the lever-arm and is divided midway in the groove, both parts being screwed onto the thrust-rod, so that they may be jammed to 130

gether and all danger of the collar working up or down on the rod prevented, while at the same time it is adjustable to compensate for wear in the connections of the lever. Its separability also facilitates the assembling of the parts. The action of this governor is the familiar one—to wit, that the centrifugal force of the weighted lever-arms O' , by spreading them, tends to cause the inwardly-projecting fingers O^{10} to pull down the shaft O^2 and rock the lever $P P'$. The cam J^{10} on the gear-wheel J' is so located as to collide with the roller L^{14} and push outward the plunger L^{12} at proper time to open the gas-inlet valve once in each two revolutions of the main crank-shaft. At starting, the wedge-shaped end of the rod L^{11} is lodged in the notch in the terminal l^{12} of the plunger L^{12} , so that when the cam reaches the roller it will operate the valve-stem through the medium of the plunger L^{12} . When the cam runs off the roller, the spring L^{13} retracts the plunger and the spring N closes the valve, the movement of the valve and stem being a little less than that of the plunger, so that the notched terminal l^{12} of the latter is withdrawn from the wedge end of the stem, though the parts remain in line ready to become again engaged at the next return of the cam unless the governor in the meanwhile deflects the stem L^{11} more than the width of the notch l^{12} . The rotary speed of the governor may rise until the wedge-shaped end of the stem L^{11} is deflected any amount less than the width of the notch; but if the speed rises sufficiently to cause the lever $P P'$ to carry the stem or rod L^{11} so far out of line with the plunger-terminal that the wedge-point misses the notch of the plunger-terminal the further reciprocation of the plunger by the further rotation of the main crank-shaft and of the gear-wheel J' will be unavailing to open the valve, because the plunger will reciprocate past the point of the rod L^{11} without colliding with it. As the speed diminishes from the lack of power thus cut off, the governor-balls falling will permit the lever $P P'$, pressed by the spring Q , to swing the rod L^{11} back into line with the plunger, and thereupon the next time the plunger is pushed forward by the cam it will engage the rod and operate the valve.

Any diminution of the speed below the normal point will occur only when the resistance of the work being done exceeds the power afforded by the engine, and the falling of the governor-balls, due to such loss of motion, will produce no effect; but the engine will soon stop from the excessive proportion of gas. The engine, however, will not ordinarily stop with the gas or oil inlet valves open, because the cam operates to open these valves during the air-compressing stroke of the piston, and if it should chance to stop at this point the reaction of the compressed air would throw it back and carry the cam off the roller L^{14} and allow the valve to close.

Thus far it has been assumed that the

proper quality of gas or mixture of gas and air is drawn into the cylinder past the gas-inlet valve. For the purpose of producing a proper mixture we provide the carburetor or vaporizing chamber or mixing-chamber M , which, as already stated, communicates with the valve-chamber D and thence with the cylinder. In this carburetor or mixing chamber M we provide a wheel having oblique vanes $S S S$, set preferably at an angle of about forty-five degrees, and we have usually provided the wheel with four such vanes, so that each vane overhangs the next a short distance. The hub S' of the wheel is a sleeve which obtains bearing upon the hollow boss or fixed sleeve M^{21} , which projects upward from the diametrical cross-bar M^{20} , formed across the bottom of the cylindrical shell M^2 , which constitutes the wall or lining of the chamber, and which is inserted and secured within the outer casting of the carburetor or mixer M . M^3 is a perforated or woven-wire bottom which is provided for the carburetor or mixing chamber and which is supported on the cross-bar M^{20} . The vanes $S S S$ of the wheel extend close to the inner surface of the lining M^2 . M^4 is the cover of the carburetor or mixer, which constitutes an extension of the chamber upward above the top of the wheel and of the lining M^2 . It has an air-inlet M^{40} , which preferably leads out laterally and opens downwardly, as shown. At the center of the top of the cover the plug R is inserted, which has a vertical bore R' , leading into a valve-chamber R^2 , the bottom of which constitutes a seat for the valve R^3 , whose fluted stem R^{30} is guided in the bore R' , while the valve seats at the upper end of said bore—that is to say, at the bottom of the chamber R^2 . Within the cover M^4 there is secured to this valve-stem a disk R^5 , whose upper surface is sloping, being in the form of a segment of a sphere or cone and of sufficient diameter to overhang the hub of the carburetor-wheel. The stem is continued down below this disk, but the lower portion R^{31} need not be fluted, but is shown cylindrical and is guided within the tubular boss M^{21} , protruded below the cross-bar M^{20} , overhanging the stem L' of the valve L . Within the passage M' there is fulcrumed on the wall thereof the trip-lever T , one end of which is adapted to be engaged in the notch l in the upper side of the valve-stem L' , while the other end is adapted to operate against the lower end of the stem R^{31} . The notch l has one end abrupt and adapted to engage abruptly the trip-lever and rock it about its fulcrum to cause it to push the valve-stem R^{31} upward when the valve L is pushed off its seat and to withdraw from it abruptly and allow it to fall and permit the valve-stem R^{31} to fall when the valve L comes to its seat. The plug R has a horizontal arm R^4 , into which an oil-pipe E^6 is connected laterally, and through which a duct r^4 leads into the chamber R^2 , and in which there is provided the needle or taper valve V , of familiar construction, adapted to seat in

the tapering inlet r' , which leads to the duct r^4 and controls the fluid supply, which by reason of the long taper of the valve and its seat may be thus regulated with extreme accuracy. The stem of this valve emerges through a stuffing-box at the end of the horizontal arm R^4 , and is provided with a handle V^2 outside the same. It may now be understood that the air which is drawn into the cylinder by 10 the outward movement of the piston therein is drawn through the air-inlet M^4 , leading to the carburetor-chamber, and in order to reach the cylinder had to pass the vaned wheel in the carburetor, and that being thus drawn 15 through that wheel against its oblique vanes it, induces a rapid rotation of the wheel; also, that when the gas-inlet valve is open the cut-off valve R^3 is also open, and that fluid is admitted through the flutes or grooves of 20 the stem R^3 into the carburetor and in case of oil flows out over the margin of the disk R^5 and falls onto the sloping surface of the vanes which are thus revolving, and thereby reaches 25 a large quantity of air, so that the oil which, in addition to its tendency to flow by gravity down the sloping surface of the vanes, will also by centrifugal force be carried toward the outer margins thereof and thus spread over the whole surface will be rapidly vaporized and taken up by the air as it passes, so 30 that the current which is drawn past the gas-inlet valve into the cylinder is highly charged with inflammable vapor and in condition for explosion upon ignition. The purpose of the 35 perforated or woven-wire bottom of the carburetor is to arrest, as far as possible, the particles of dust which will of necessity enter with the air and which would tend to clog the valves and wear the cylinder. The cut-off 40 valve R^3 being opened to admit fluid to the carburetor only when the gas-inlet valve is open to admit gas to the cylinder, and remaining open only for a certain proportion of the 45 duration of the stroke of the gas-inlet valve, determined by the relation of the notch l' to the lever T and end of the stem R^3 , an approximately-uniform quantity of fluid will be admitted to the carburetor at each stroke, this 50 quantity being limited by the regulator-valve V , which will be set so that in the intervals of the openings of the cut-off valve only the predetermined quantity of fluid can flow into the chamber R^2 .

There will be some variation in the quantity of oil which will be admitted when the governor has interrupted the action of the valves for one or more cycles of the engine, because in the longer interval a larger quantity of oil will have accumulated in the chamber R^2 . This variation is not considered important, and will not exist in the case of gas admitted past the valve V . When this valve is properly set, in view of the rate at which the engine is desired to run and the work which it is to do, the operation will be substantially unvarying while those conditions prevail; but if any change of work increases

the speed or diminishes it below the point for which the engine is adjusted the governor will either temporarily cut off the supply until the speed diminishes or will stop the engine if its speed becomes too low. 70

The length of time that the gas-inlet valve and the cut-off valve are held open depends upon the extent of the cam J^{10} , and as it may be desirable to vary this somewhat, according to the experience with each engine, which may vary under known conditions or with slightly-different qualities of fluid, requiring more or less time for vaporization, and according to other conditions, we have only made this cam adjustable in the manner shown in Fig. 6 by making it in two parts, each being a short segment of a ring adapted to be bolted onto the back of the gear-wheel, 80 as shown, one cut away at the inside and the other at the outside, so that they may be lapped one upon the other and slide one upon the other in adjusting them, so that at their lapping portions the roller L^{14} will bear upon 90 both sections, one end traveling upon one section until the other end enters upon the other section.

The manner of securing the sections of the cam to the web of the wheel may be understood from Fig. 1 and the detail Fig. 7, a web j^{10} in a plane at right angles to the axis of the wheel being thrown across the angle between the principal spherical web and the web of the gear-rim, and this web j^{10} being provided with a slot j^{11} , into which a rib J^{11} , formed upon the back of each of the cam-sections, enters and thus serves to guide the cams in their adjustment and hold them definitely in their proper positions with respect to the wheel, a bolt j^{13} being inserted through each section of the cam and a nut on the inner end of it in the cavity behind the web j^{10} binding against the inner face of that web, serving to secure the sections firmly in place as adjusted, the outer head of the bolts being slotted, so that they may be tightened from the exterior, since no access can be had in the cavity to engage the nuts. The amplitude of the slot j^{11} is made sufficient for the utmost adjustment of 115 the cam-sections.

It will be observed that the degree to which the governor-balls must be spread before they cause the governor to interrupt the action of the gas-inlet valve depends upon the tension of the spring Q , and that this spring can be adjusted by the screw Q' while the engine is running, and the details of the construction and location of the governor and its connections are contrived to this end. 120

When the gas is admitted past the regulator-valve V and cut-off valve R^3 , the revolving vaned wheel in the chamber M performs only the function of thoroughly intermixing the gas and air; but when oil is admitted the chamber and revolving vaned wheel therein become a carburetor or vaporizer, as well as a mixer. 130

When gas is supplied to the chamber M past

the valves V and R³, the passages should be larger than when these passages admit an oil supply.

We claim—

- 5 1. In combination with the vertical carburetor, the horizontal gas passage therefrom to the cylinder, the gas inlet valve having its stem extending through said passage below the carburetor; the oil inlet valve of the carburetor having its stem extending down through the latter, and the lever T fulcrumed within the horizontal gas passage and engaged by the gas inlet valve stem and engaging the oil inlet valve stem; substantially as set forth
- 10 2. In a gas engine, in combination with the cylinder, a carburetor or oil vaporizer having its chamber communicating with the cylinder and comprising a vaned wheel vertically journaled in said chamber, and having oblique vanes and adapted to be revolved by the passage of air therethrough, said chamber having an oil inlet located above the center of the vaned wheel and a distributing disk onto 15 which the oil falls through the oil inlet, and from which it falls onto the vanes of the wheel; substantially as set forth.
- 20 3. In a gas engine, in combination with a main driving shaft and a driven shaft at right angles thereto, and driving and driven beveled gears on said shafts respectively; the gas inlet valve and a reciprocating plunger which actuates it and the cam on the back of the driven wheel to actuate the plunger; substantially as set forth.
- 25 4. In a gas engine, in combination with the main driving shaft and a driven shaft at right angles thereto, and the driving and driven

beveled gears on said shafts respectively proportioned to give the driven shaft half of 40 the rotary speed of the driving shaft; the lighter valve and the exhaust valve, and the cams on the driven shaft which operate each of them once in each revolution of said shaft, and a cam on the back of the driven beveled 45 gear, and the gas inlet valve operated by such cam; substantially as set forth.

5. In a gas engine, in combination with the main driving shaft and a driven shaft parallel with the path of the piston, and driving and driven beveled gears on said shafts respectively, the gas inlet valve having its stem reciprocating parallel to the driven shaft and between the same and the path of the piston; a cam on the driven beveled gear, and the 55 plunger in line with said valve stem and in position to be actuated by said cam to operate the valve; the governor mechanism overhanging and driven by said driven shaft, and the bell-crank-lever having its horizontal arm connected to and adapted to be oscillated by the governor; and its vertical arm engaging the stem of the gas inlet valve, whereby the action of the governor swings said stem horizontally out of the path of the plunger; substantially as set forth.

In testimony whereof we have hereunto set our hands, at Chicago, Illinois, in the presence of two witnesses, this 3d day of May, 1894.
